PISTON PACKING RING

Frank D. Frisby, St. Louis, Mo., assignor to Frisby Corporation, St. Louis, Mo., a corporation of Missouri

Application September 3, 1949, Serial No. 114,028

16 Claims. (Cl. 309—44)

1

This invention relates to improvements in composite piston packing rings of the general class described in my United States Letters Patent No. 2,459,157 dated January 18, 1949.

This invention is embodied in a piston packing ring comprising a flexible sealing element and an integrant tensioning element in cooperative relation therewith.

A helical ring element, as it is known in the trade, may have a crimp in its middle coil (or coils) for insuring that the outer coils will lie in parallel planes. A spiral ring element, as it is known in the trade, may have a crossover therein for insuring that the inner coils will be concentric with the outer coil, the coils generally being large segments of circles. A helico ring is a combining form of a helical ring and a spiral ring and has an internal frictional surface on a plane parallel to the axis of the ring and also an internal frictional surface on a plane at right angles to the axis, with a positive interaction due to the bonded assembly of the elements acting as one continuous piece or part, so as to utilize the frictional surfaces described.

The helico ring has the ability to transmit tension with uniform distribution around the sealing element's entire outer circumference and to maintain circularity of the sealing contact with the cylinder wall.

The principal object of the present invention is to provide a packing ring, formed from two separate elements and preferably made from two different materials or alloys bonded or attached together to form a one piece helico ring assembly for the purposes hereinafter described.

Another object is to provide a piston packing ring having a variable high degree of internal frictional resistance within an element (or elements) and between the elements when the ring is forced to contract (or wind up) in a cylinder because of torsion, taper, or wear in the surface of the cylinder wall. This action provides unusual resistance to ring collapse and improves the compression and oil control properties of the ring.

Another object of the present invention is to provide a packing ring of the type hereinafter described in which the torsional effect may be obtained in either direction (up or down) by correctly positioning the contact point on the face element with respect to the radial force position of the expanding element to provide a concentric sealing action.

Still another object is to provide packing rings of forms and materials which will improve pre-

cision die and rolling methods of manufacture and reduce machining operations to a minimum to produce a low cost, efficient packing ring having a long service life.

5 A helico ring of two or more turns combines the desirable characteristics of both a helical ring and a spiral ring in one ring, one turn being a flexible sealing element made from a material providing the most compatible sealing relation-

10 ship with a cylinder wall.

The object of dual rings as shown in Fig. 16 is to produce a better coordination of action and efficiency in a compact form through a desired combination of elements in a piston ring groove.

15 This arrangement is particularly effective for the new high compression engines where maximum compression and oil control are required for a minimum area on short headed pistons (the distance from the top of a wrist pin hole to the

20 top of a piston).

In the helico ring hereinafter described, the expander element has a high degree of circularity and is in contact with the sealing or face element around said sealing element's inner circumference, said circularity being transmitted and reflected in the precision concentricity of the sealing element's outer circumference in contact with the cylinder wall surface.

25 The helico ring may be preloaded and is shown in expanded preloaded form in Fig. 1 so that the expander element exerts a tension of a desired degree. The preloading may be accomplished by rolling the expander element to a larger free diameter than the free diameter of the recess in the

30 sealing element with which the expander element is to cooperate. Accordingly, the expander element is under a degree of tension when assembled in the sealing element. It is preferable to load the sealing element so that its inside diameter is approximately equal to the outside diameter of the piston head, so that little additional expansion is necessary to install the ring on the piston head. This combination facilitates installation on a piston and substantially increases the

35 efficient service life of the ring.

40 The invention also consists in the combinations and arrangements of parts hereinafter described and claimed.

45 In the accompanying drawings, which form part of this specification, and wherein like numerals and letters refer to like parts wherever they occur:

46 Fig. 1 is a normal, full size scale bottom view
50 of a helico ring having an expander element

bonded to a tapered compression ring in expanded preloaded form.

Fig. 2 is a side elevational view of the combination shown in Fig. 1.

Fig. 3 is a bottom view of a pair of spiral expanders bonded or attached to a pair of torsion compression rings at the points indicated by the marks "X," each ring having independent action; this figure and the following figures show the rings in contracted form with enlarged thicknesses with respect to their diameters for clarity.

Fig. 4 is a side elevational view of the combinations shown in Fig. 3.

Fig. 5 is a bottom view of a spiral expander element, formed by bonding separate turns, bonded to a sealing element.

Fig. 6 is a side elevational view of the combination shown in Fig. 5.

Fig. 7 is a bottom view of a helico ring.

Fig. 8 is a side elevational view of the ring shown in Fig. 7.

Fig. 9 is a bottom view of another helico ring.

Fig. 10 is a side elevational view of device shown in Fig. 9.

Fig. 11 is a plan view of a torsion scraper compression ring bonded at one point to a single expander element for forming a helico ring.

Fig. 12 is a side elevational view of the device shown in Fig. 11.

Fig. 13 is a cross-sectional view taken along the line 13—13 in Fig. 11.

Fig. 14 is an enlarged fragmentary view of a portion of the device shown in Fig. 11.

Fig. 15 is an enlarged vertical cross-sectional view of a piston head equipped with my new rings.

Fig. 16 is an enlarged vertical cross-sectional view of a piston head equipped with my new rings for use particularly effective on short headed pistons, and

Fig. 17 is a side view of ring G in Fig. 15.

The piston ring construction A shown in Fig. 1 is a helico ring in normal, full size and in expanded preloaded form prior to insertion in a groove on a piston head. The ring construction A comprises a sealing element 1 having a gap 2 and recess 3 therein, and an expander element 4 bonded or attached to said ring 1 at the place indicated by the marks "X."

In the piston ring construction B shown in Fig. 3, a spiral expander element 5 with a cross-over 6 at its center is bonded at the point "X" to a sealing element 7 having a tapered face 8 with a large corner radius 9. Obviously the face may be varied according to the action the sealing element is to perform.

The piston ring construction C shown in Fig. 5 consists of a spiral expander 10 formed by bonding separate turns which contact each other, as in the aforesaid construction, in a form of concentric circularity over a wide range of action (circumferential expansion and contraction) through which a piston ring may be subjected during the stroke of the piston. The gap 11 of the sealing element is preferably displaced about 90° from the bonding. In this construction, as in all the other constructions containing a gap and a bond, the bond is placed at a selected point where it is most favorable to a uniform distribution of radial force and frictional resistance between the elements.

The piston ring construction D shown in Fig. 7 is a helico ring comprising a torsion scraper compression ring 12 having a solid radial wall with a single turn expander element 13 bonded

or attached at the place indicated by the marks "X." The gap 14 is preferably near the bond in this construction although it may be at any desired point. A modified form E of this construction is shown in Fig. 9 wherein a sealing element or oil control ring 15 with drainage slots 16 is bonded to a single expander element at the place indicated by the marks "X." This oil control ring 15 has dual scraper lands 17 on the face of the sealing element. The gap 18 in this construction is preferably removed from the bond.

An improved torsion scraper compression ring F shown in Fig. 11 has an expander element 19 and a sealing element 20 bonded at one point, preferably by die forming methods. The expander element 19 rests in a continuous annular channel 21 at the inner circumference of the sealing element 20 which has a retaining edge to hold the expander element in assembled position around its circumference while in preloaded form. A continuous recess 22 is provided around the outer circumference of the sealing element for oil scraping and torsion action as indicated by the arrow. As the expander element 19 applies radial force at a point below the sealing face, the sealing element twists into a torsion position permitting the large corner radius 23 on the outer circumference of the sealing element 20 to create an excellent seal between the ring elements, cylindrical wall and the piston ring groove 24. The sealing element 20 may have a partly slotted radial wall (approximately 50%) for maximum flexibility of action with eight supporting sections left for structural stability of the ring.

Fig. 15 is an enlarged vertical cross-sectional view of a piston head equipped with my new rings. A heat dam 25 is located in the upper portion of the piston head 26. The ring G is a torsion metering compression ring having a single turn flat section expander element 27 bonded thereto. The face 28 of the sealing element is tapered and has a large corner radius 29 thereon. This ring G is designed to twist in the direction shown by the arrow. Each of the rings A, G, F and E is fitted into its respective groove with the usual clearance.

Fig. 16 is an enlarged vertical cross-sectional view of a short headed piston 30 having a heat dam 31 and an upper groove 32 and a lower groove 33 for receiving two pairs of my ring constructions in a desirable combination. The short headed piston 30 shown has a pair of helico rings as shown in Fig. 7 and Fig. 8, in the upper groove 32 each of said helico rings comprising a single turn expander element bonded to a torsion scraper compression ring. In the lower groove 33 is a pair of piston rings each comprising a sealing element with a large corner radius and a spiral expander element.

The various expander elements disclosed herein may be combined with various sealing elements in numerous combinations. Similarly, different pairs of rings may be placed in the two grooves on the short headed piston according to the results desired.

The continuous annular channel 21 may be combined with any of the sealing elements and may be formed with a curved inwardly facing wall as shown in Fig. 13 or a sloping wall as shown in Fig. 17 to insure intimate frictional contact between the elements over their entire area of contact during operation.

In operation, the rings hereinbefore described do not depend on a radial expanding force alone,

but depend on a controlled combination of radial expanding force and a contracting action in which there is increasing frictional resistance between the elements, which have no contact with the bottoms of the grooves.

Conventional expander elements depend on expanding radial force which becomes greatly reduced as wear increases so that their life of efficient service is reduced. When wear appears on the contacting surfaces of the helico ring constructions hereinbefore described, the variable shape of the cylinder controls the contracting action of the expander element and regulates the internal frictional resistance to changes in diameter and shape of the cylinder wall so that the greater the wear, the greater the winding and unwinding action, and therefore, the greater the frictional resistance increase between the elements. This frictional resistance is of an instantaneous nature in operation.

What I claim is:

1. A piston packing ring comprising an annular sealing element having a gap therein, and an expander element positioned in said sealing element and bonded thereto at one point to form a helico ring.

2. A piston packing ring comprising an annular sealing element having a gap therein, and said sealing element having an annular channel on its inner circumference, an expander element positioned in said annular channel and bonded to said sealing element at one point to form a helico ring.

3. A piston packing ring comprising an annular sealing element having a gap therein, said sealing element having a peripheral recess therein along an inner edge thereof and an expander element of at least one turn and positioned in said recess in said sealing element and bonded thereto at one point.

4. A piston packing ring comprising an annular sealing element having a gap therein, said sealing element having an inner peripheral recess therein along an inner edge thereof, and an expander element having a free diameter larger than the free diameter of the recess with which it is to cooperate and bonded thereto at one point.

5. A piston packing ring comprising an annular split sealing element, and an expander element of at least one turn and positioned in said sealing element and bonded thereto, said ring capable of expanding outwardly because of radial pressure and resisting circumferential contraction because of positive instantaneous frictional resistance between said elements.

6. A piston packing ring comprising an annular split sealing element having an annular recess therein, an expander element of at least one turn positioned in said recess and bonded thereto at a point to create a positive instantaneous opposed reaction between said elements over their area of contact.

7. The combination set forth in claim 6 wherein said sealing element is preloaded to an inside diameter approximately equal to the outside diameter of the piston head on which said sealing element is to be installed.

8. A piston packing ring comprising an annular sealing element having a gap therein and a large corner radius thereon, said sealing element having an annular channel on its inner circumference, and an expander element positioned in said annular channel and bonded to said sealing element at one point to form a helico ring.

9. The combination set forth in claim 8 wherein the inwardly facing wall of said annular channel is provided with an angle to increase frictional pressure between the elements.

5 10. The combination set forth in claim 8 wherein said expander element applies radial force at a point so that the sealing element twists into a torsion position.

10 11. A piston packing ring comprising an annular split sealing element having an annular recess therein, an expander element of at least one turn positioned in said recess, one end of said expander element overlapping an opposite end of said sealing element and bonded thereto to provide a positive opposed frictional reaction between the elements over their area of contact.

11 12. A piston packing ring comprising an annular split sealing element, and an expander element disposed within the side wall of said sealing element and bonded thereto, said expander element being in the form of a spiral operating expansively against the sealing element on all points in its circumference.

12 13. A piston packing ring comprising an annular split sealing element having a gap therein, and an expander element disposed within said sealing element and bonded thereto, said expander element being in the form of a spiral of at least two turns, said spiral operating expansively against the sealing element.

13 14. A piston packing ring comprising an annular sealing element having a gap therein, and an expander element disposed within said sealing element and bonded thereto, said expander element being in the form of a spiral operating expansively against the sealing element.

14 15. A piston packing ring comprising an annular sealing element having a gap therein, and an expander element disposed within said sealing element and bonded thereto, said expander element being formed by two separate turns bonded together to form a spiral, said spiral operating expansively against the sealing element.

15 16. A piston packing ring comprising an annular sealing element having a gap therein, and an expander element disposed within said sealing element and bonded thereto at approximately 90° from said gap, said expander element being formed by two separate turns bonded together to form a spiral, said spiral operating expansively against the sealing element.
